UNITED STATES PATENT OFFICE

91,995

DESIGN FOR AN ELECTRIC RANGE OR SIMILAR ARTICLE

John Fletcher, New York, N. Y., assignor to Electric Trading Corporation, New York, N. Y., a corporation of New York

Application February 12, 1934, Serial No. 50,685

Term of patent 14 years

To all whom it may concern:

Be it known that I, JOHN FLETCHER, a citizen of the United States, and a resident of the Borough of Manhattan, city, county and State of New York, have invented a new, original, and ornamental Design for an Electric Range or Similar Article, of which the following is a specification, reference being had to the accompanying drawing, forming a part thereof.

Fig. 1 is a perspective view of an electric cooker

showing my new design with the heating elements in operative position disposed against the body of the cooker;

Fig. 2 is a similar view thereof with the heating elements in inoperative position, swung apart from the cooking chamber.

I claim:

The ornamental design for an electric range or similar article, as shown and described.

JOHN FLETCHER.
